UNITED STATES PATENT OFFICE.

JOHN J. LANGMACK, OF PORTLAND, OREGON.

AUTOMATIC OIL-PUMP WITH SIGHT-FEED.

Specification of Letters Patent. Patented June 15, 1920.

1,343,677.

Application filed June 14, 1917, Serial No. 174,819. Renewed September 2, 1919. Serial No. 321,240.

To all whom it may concern:

Be it known that I, JOHN J. LANGMACK, a citizen of the United States, residing in the city of Portland, county of Multnomah, and State of Oregon, have invented certain new and useful Improvements in Automatic Oil-Pumps with Sight-Feed, of which the following is a specification.

My invention relates to an automatic oil pump adapted to feed oil, under force, to cylinders, bearings and other mechanical parts requiring constant lubrication, and it has among its salient objects to provide in a device of the character referred to a reservoir with a removable cover, and a pumping mechanism capable of being bodily lifted from said reservoir without the necessity of taking the same apart, for such cleaning, adjustment or repairs, as may from time to time be necessary; to provide in a device of the character referred to an operating mechanism which can be quickly adjusted for use with right or left hand connections; to provide in a device of the character referred to a sight feed of such construction that any clogging of the oil passageways will be promptly indicated thereby, there being no escape for the oil around the sight feed mechanism which will prevent its filling the sight feed tube and thus indicating promptly that there is an obstruction somewhere in the mechanism.

Other objects and advantages will be apparent from the following description of the preferred embodiment of my invention, taken with the accompanying two sheets of drawings on which the same is illustrated, and which I will now describe. In the drawings,

Figure 1 is the top plan view of an automatic oil pump embodying my invention, taken on line 1-1 of Fig. 3;

Fig. 2 is a horizontal, sectional view thereof, taken on line 2-2 of Fig. 3;

Fig. 3 is a vertical, sectional view thereof;

Fig. 4 is a side elevation of a ratchet mechanism, the main body, or casing, being shown in dotted lines;

Fig. 5 shows end and longitudinal, sectional views of a feed connecting member attached to the body or casing;

Fig. 6 is a fragmentary, vertical, sectional view through a sight glass, taken on line 6-6 of Fig. 2; and

Fig. 7 is a vertical, sectional view through a check valve member for connecting the oil

feed to the cylinder box, or other bearing, which is to be lubricated.

Referring now in detail to the drawings, my invention, as here illustrated, comprises a box, or casing, 1, constituting a reservoir for the lubricating material, and provided with means, as at 1^a, for securing it in a suitable position for operation. Said box, or casing, 1, is provided with a removable cover 2, having a trap door 3, covering a screen 4, through which lubricating matter is supplied to said reservoir. Said cover is also provided with a glass 5, securely mounted in a metal frame 6, with sight openings therethrough, as indicated. Thus said cover can be removed bodily without difficulty.

Said box, or casing, is provided in the upper edges of its opposite end walls with openings, as at 1^b-1^b, into which detachably fits filler bearing members 7-7. Mounted within said box, or casing, is a plunger casting, or body, 8, of substantially the form shown in Fig. 3, having a longitudinal oil passageway 8^a, extending therethrough at one side of the center, as seen in Fig. 2, said passageway being provided at its lower end with a ball valve 8^b, controlling the inlet thereto, but preventing oil from being forced out at the lower end of said passageway. A screen 9, is placed around the lower end of said member 8, in the manner indicated. Formed as a part of said plunger casting, or body, 8, is a hollow, L-like extension 8^c, having a plunger 10 reciprocating therein and adapted to force oil upwardly through said passageway 8^a. Said plunger casting 8 is also formed near its upper end with a transversely extending plunger chamber 8^d. It also has an extension 11, projecting through the detachable filler bearing member 7, and provided with a nut 12, for securing the casting, or body, 8, securely to said removable member 7, as clearly shown in Figs. 2 and 3. Said extension is provided with an oil passageway 11^a, therethrough, communicating with the transversely extending plunger chamber 8^d, as indicated in dotted lines, Fig. 3, which oil passageway 11^a, is intersected by two tapered, check-valve chambers 11^b and 11^c, having ball valves therein, as clearly indicated, which will permit oil to be forced outwardly through said oil passageway 12^a, but will prevent any back flow therethrough. Also formed in the upper end of said plunger casting is a vertical oil

passageway 8^e, flared at its upper end, as at 11^c

8^t, and at its lower end communicating with the transversely extending plunger chamber 8^a. Connected to the upper end of the oil passageway 8^a, which extends longitudinally through said casting 8, at one side of the center thereof, is a crooked feed spout 13, adapted to direct oil forced upwardly through the oil passageway 8^a, by the plunger 10, into the flared upper end 8^t of the oil passageway 8^e, which terminates at its lower end in the plunger chamber 8^a.

A short glass sight tube 14, is set around the crooked feed spout 13, upon the upper end of the plunger casting 8, and is secured 15 in place by a cage-like member 15, screwed onto the upper end of the casting 8, as clearly indicated in Fig. 3. This construction permits the removal of the cover 2, together with the outer sight glass 5, and its 20 frame 6, without the disturbance of the inner sight glass 14 and its holding cage 15. It will also be noted that for any reason the oil passageway 8^a, which is flared at its upper end at 8^t, is filled with oil, the oil will 25 fill the inner sight tube 14, and thus disclose the fact that there is an obstruction in the oil circulating system.

A plunger 17, is mounted to reciprocate in the plunger chamber 8^a, and is attached at 30 one end to an operating yoke 18, the lower side of which yoke has a sliding engagement, as at 19, with an extension 20, formed as a part of the plunger casting 8. The opposite side of said yoke 18 has connected therewith 35 a pin 21, on which is mounted a sleeve 22, provided at its outer end with a thumb nut 23, by means of which said sleeve can be turned. Said sleeve has a slot and pin connection, as at 24, with the pin 21. A coiled spring 25, is mounted around the pin 21, within the sleeve 22, as indicated. Also mounted on the pin 21, and having a toothed, interlocking engagement with the end of 40 said sleeve 22, as at 26, is a sleeve extension 27, having threaded engagement with the pin 21, and provided with a downwardly depending portion 28, having a slot 29, therein, adapted to receive an operating pin 30, mounted upon the upper end of a rocker lever 45 31, pivotally connected in its middle, as at 32, to the extension 20. The lower end of said rocker lever 31, is connected by means of 50 a link 33, to the outer end of the plunger 10.

Detachably mounted through the casing, 55 or housing, 1, in detachable bearing members 34 and 35, is a shaft 36, on which is mounted an eccentric disk 37, within the yoke 18, and by means of which said yoke 18, with its plunger 17, and its other connected parts 21, 60 22 and 27, are reciprocated. Secured on said shaft 36, is a ratchet wheel 38. Secured to the outer end of said shaft 36, is a crank disk 39, provided with a handle 40. Loosely mounted on said shaft is an operating 65 wheel 41, provided around its periphery

with a series of sockets in which are inserted screws 41'—41'. Secured in one of said sockets in said wheel is a rod 42, projecting downwardly, as clearly indicated in dotted lines, Fig. 3, said rod having adjustably connected to its lower end, by means of a connecting member 43, an operating rod, or pitman, 44, which can be connected to any moving part of the engine, or mechanism, upon which my device may be mounted. Mounted upon the bearing member 35, which is detachably seated in an opening in the side of the casing 1, is a bracket member 45, said bracket member being secured to said bearing member by means of a split collar 46, and a screw 47. Mounted on said bracket 45, is a holding pawl, or dog, 48, normally held in holding position with the ratchet wheel 38, by means of a spring 49. Mounted upon and secured to the inner end 8 of the wheel hub, adjacent the ratchet wheel 38, is a bracket 50, similar to the bracket 45, which bracket 50, is provided with an operating pawl, or dog, 51, held in operating engagement with the ratchet wheel 38, by means of a spring 52, whereby as said wheel 39, is given a rotary oscillating movement, it operates through said bracket 50, and said pawl 51, to step forward said ratchet wheel 38, which is secured to the shaft 36, by means 95 of a key, or feather, 36^a.

Thus said shaft 36, and its eccentric cam can be directly operated by hand by means of the disk 39 and handle 40, or said hand wheel 41, can be oscillated through the connection made to the pitman 44, with a moving part of the engine, whereby said ratchet wheel 38, is stepped forwardly, notch by notch, operating the shaft 36, and the eccentric 37, by means of which the yoke 18, is operated with its plunger 17, and through the connection of the rocker arm 31, the plunger 10, is also operated, said plungers 10 and 17, being alternately moved forwardly. As the plunger 10 moves outwardly, it draws oil 11 through the inlet at 8^b, at the lower end of the oil passageway 8^a, and as said plunger is forced inwardly said oil is forced upwardly through said passageway 8^a, feed spout 13, from which it drips into the 11^t passageway 8^a, and into the plunger chamber 8^a. As the plunger 17, moves inwardly, it forces the oil, thus fed into the plunger chamber 8^a, out through the extension 11, past the check valves 11^b and 11^c, from which 120 said oil is carried by straight pipe connections to the cylinders, boxes and bearings to be lubricated.

By means of the sleeve 22, on the pin 21, which pin is revolvably connected to the yoke 18, as at 21, the sleeve extension 27, can be adjusted to different positions on said pin 21, whereby to regulate the stroke of the piston 10. This adjustment is accomplished by pulling outwardly on the thumb nut 23, 125

against the tension of the spring 25, and by turning said thumb nut and said sleeve, the pin 21, being turned in one direction or the other, as may be desired, whereupon the 5 sleeve extension 27, is moved in one direction or the other, on said pin, by reason of its threaded connection therewith.

Mounted in one corner of the box or casing, 1, is a glass sight tube 53, open at both 10 ends for indicating the height of the oil supply in the box, or casing, 1.

In attaching the distributing pipes for feeding the oil directly to the cylinders, boxes, or other bearings, to be lubricated, I 15 prefer to use a check-valve mechanism, similar to that shown in Fig. 7, and similar to the check-valve mechanism controlling the oil discharge from the plunger chamber 8^a, by the plunger 17. For example, P indicates 20 a steam pipe, and 54 a feed pipe from the extension 11, for feeding oil to the steam pipe P, said check-valve mechanism comprising a casing 55, with the irregular oil 25 passageway 56, therethrough, with the spring-pressed ball valves 56^a—56^a, interposed in the tapered vertical portions of the oil passageway 56, through said member 55, for preventing the back flow of the oil, in a manner which will be well understood from 30 the drawings.

Attention is hereby called to the fact that by reason of my improvements, the cover 2 can be bodily removed from the box, or casing, 1, leaving the entire mechanism exposed, 35 and without disturbing the sight feed.

Attention is also called to the fact that by reason of the removable bearings 34 and 35, which are seated in the upper outer edges of said box, or casing, the shaft 36 and the 40 parts mounted thereon can be bodily lifted out of the machine and out of the yoke 18, and reversed, or changed end for end, whereby to put the driving connections at the opposite end of the casing.

45 Attention is also called to the fact that the entire mechanism can be bodily lifted out of the box, or casing, by reason of the fact that the bearing members 7—7, in the opposite ends of the box, or casing, are detachably seated in the upper edges thereof.

50 Thus I have provided an improved mechanism in which all of the working parts are wholly inclosed within the reservoir away from the dust and dirt, and in which the 55 parts can be quickly and conveniently lifted out for the purpose of cleaning, repairing, or reversing, without the removal of bolts, screws, and the like.

While I have shown the preferred and 60 latest developments in my improved oil pump, I do not limit it to the details here shown, except as I may be limited by the hereto appended claims.

I claim:

65 1. In a device of the character referred to,

a box constituting a reservoir for lubricant and having openings opposite each other in its upper edge, a pumping mechanism in said box and detachably seated in said openings, whereby it can be lifted bodily therefrom, and a removable cover for said box, substantially as described. 70

2. In a device of the character referred to, a box constituting a reservoir for lubricant and having openings in its upper edge opposite each other, filler members detachably seated in said openings, a pumping mechanism having portions extending through said filler members, whereby said pumping mechanism and said filler members can be 75 so lifted bodily out of said box, and a cover adapted to the upper edge of said box, substantially as described.

3. In a device of the character referred to, a box constituting a reservoir for lubricant 85 and having openings opposite each other in its upper edge, a pumping mechanism in said box and detachably seated in said openings, whereby it can be lifted bodily therefrom, said pumping mechanism having a 90 drip spout for feeding the oil, with a sight tube around the same formed as a part of said pumping mechanism and removable therewith from said box, and a cover for said box having a sight tube adapted to fit 95 over said drip spout and its inclosure, substantially as described.

4. In a device of the character referred to, a box constituting a reservoir for lubricant and having openings in its upper edge opposite each other, filler members detachably seated in said openings, a pumping mechanism having portions extending through said filler members, whereby said pumping mechanism and said filler members can be 100 105 lifted bodily out of said box, said pumping mechanism having a drip spout for feeding the oil, with a sight tube around the same formed as a part of said pumping mechanism and removable therewith from said 110 box, and a cover for said box having a sight tube adapted to fit over said drip spout and its inclosure, substantially as described.

5. In a device of the character referred to, 115 a box, a pumping mechanism therein, an operating shaft detachably seated in openings in the upper edges of opposite side walls of said box, whereby said shaft can be bodily lifted out of said openings independently of said pumping mechanism, whereby to be reversed end for end, operating mechanisms 120 carried by said shaft, and a cover for the upper edge of said box, substantially as described.

6. In a device of the character referred to, 125 a box having openings in the upper edges of its opposite side walls, filler bearing members detachably seated in said openings, a pumping mechanism in said box, a shaft provided with operating mechanisms for op- 130

erating said pumping mechanism, said shaft having its bearings in said filler bearing members, whereby to be lifted bodily therewith and with its operating mechanisms out 5 of said box, and a cover for said box, substantially as described.

7. In a device of the character referred to, a box, or casing, constituting a reservoir for lubricant, and having openings cut in 10 the upper edges of its side and end walls, filler bearing members seated in said openings, a pumping mechanism connected at its opposite ends through the filler bearing members in the opposite end walls of said 15 box, whereby to be lifted bodily therefrom, a shaft with operating connections for operating said pumping mechanism, said shaft having its bearings in the filler bearing members in the opposite side walls of said 20 box, whereby it can be lifted bodily therefrom, and a cover for said box, substantially as described.

8. In a device of the character referred to, a box open at its top side and provided in 25 the upper edges of its four walls, opposite each other, with openings, a pumping mechanism detachably seated at its opposite ends in the openings in the upper edges of the end walls of said box, whereby to be lifted 30 therefrom, a shaft with operating connections to said pumping mechanism seated in the openings in the upper edges of the side walls of said box, whereby to be lifted therefrom, said shaft being reversible, end 35 for end, and a cover for the top of said box, substantially as described.

9. In a device of the character referred to, a box constituting a reservoir for lubricant, a body member having an upflow oil 40 passageway therethrough and terminating at its upper end in a drip spout, said body member having a downflow oil passageway adjacent said drip spout into which the latter discharges, a sight glass seated on the upper 45 end of said body around said drip spout, and a holding cage therefore secured to the upper end of said body member and removable

therewith, whereby, if said downflow oil passageway is obstructed, said sight glass will be filled with oil, substantially as de- 50 scribed.

10. In a device of the character referred to, a box constituting a reservoir for lubricant, a body member having an upflow oil passageway therethrough and terminating 55 at its upper end in a drip spout, said body member having a downflow oil passageway adjacent said drip spout into which the latter discharges, a sight glass seated on the upper end of said body around said drip 60 spout, a holding cage therefor secured to the upper end of said body member and removable therewith, whereby, if said downflow oil passageway is obstructed, said sight glass will be filled with oil, and a cover for said 65 box having a sight glass thereon adapted to set over the sight glass mounted on said body member, substantially as described.

11. In an oil pump of the character referred to, a body member having an upflow 70 oil passageway extending longitudinally therethrough and terminating at its upper end in a drip spout mounted on the upper end of said body member, said body member also having a downflow oil passageway 75 therethrough, from the upper end thereof adjacent said drip spout with a flaring upper end to receive the oil from said drip spout, means for forcing oil upwardly through said upflow passageway, a sight 80 tube seated upon the upper end of said body member around said upflow and downflow openings and said drip spout, and a cage for holding said sight glass firmly down on to the upper end of said body member, whereby 85 any obstruction in the downflow oil passageway will fill said sight glass, substantially as described.

Signed at Portland, Multnomah county, Oregon, this 9th day of June, 1917.

JOHN J. LANGMACK.

In presence of—

I. M. GRIFFIN,
J. C. STRENG.
